(57) **CLAIM**

The ornamental design for a service cart panel system, as shown and described.

DESCRIPTION

FIG. 1 is an exploded view of the service cart panel system of the present invention;

FIG. 2 is a top front left perspective view thereof;

FIG. 3 is a top front right perspective view thereof;

FIG. 4 is a bottom rear left perspective view thereof;

FIG. 5 is a bottom rear right perspective view thereof;

FIG. 6 is a front view thereof;

FIG. 7 is a rear view thereof;

FIG. 8 is a left side view thereof;

FIG. 9 is a right side view thereof;

FIG. 10 is a top view thereof;

FIG. 11 is a bottom view thereof;

FIG. 12 is a bottom right rear perspective view, in condition of use;

FIG. 13 is a bottom left rear perspective view, in condition of use;

FIG. 14 is a top front right perspective view thereof; and,

FIG. 15 is a top front left perspective view thereof.

The cart shown in broken lines is illustrative environment and forms no part of the claimed design.
